UNITED STATES PATENT OFFICE.

JOHN P. DRESP, OF BEATRICE, NEBRASKA.

DEVICE FOR REBORING CYLINDERS.

Application filed December 15, 1924. Serial No. 756,015.

To all whom it may concern:

Be it known that I, JOHN P. DRESP, a citizen of the United States, residing at Beatrice, in the county of Gage and State 5 of Nebraska, have invented a new and useful Device for Reborning Cylinders, of which the following is a specification.

This invention has reference to a device especially designed for use in reboring cylinders, the primary object of the invention being to provide a device of this character wherein the grinding elements may be adjusted, adapting the device for use in connection with cylinders of various diameters.

15 Another object of the invention is to provide a device of this character which will automatically center itself within the cylinder in which the same is positioned to insure a true and even boring of the cylinder.

20 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

25 Referring to the drawings:

Figure 1 is a side elevational view of a reboring device constructed in accordance with the invention.

30 Figure 2 is a sectional view taken on line 2—2 of Figure 1.

Figure 3 is a sectional view taken on line 3—3 of Figure 1.

Figure 4 is a sectional view taken on line 4—4 of Figure 1.

35 Figure 5 is a sectional view taken on line 5—5 of Figure 3.

Figure 6 is a sectional view taken on line 6—6 of Figure 1.

40 Referring to the drawings in detail, the device includes a central supporting section 5 which is supplied with laterally extending supporting rods 6 arranged in parallel relation with each other and disposed adjacent to the ends of the supporting section 5.

45 Arranged adjacent to the rods 6 and disposed slightly above the rods 6 are the supporting rods 7 that extend in directions at right angles to the rods 6, as clearly shown 50 by Figure 1 of the drawings.

55 Mounted on the rods 6 and 7 are the ad-

justable supports 8 which are formed with end portions 9 that have openings to accommodate the rods 6 and 7 so that the supporting members will be connected with the 60 central supporting section 5 in a manner to permit of lateral movement of the supporting members but restrict vertical movement thereof with respect to the supporting section 5.

65 Formed integral with each supporting section and extending inwardly therefrom, is a rib 10 which is formed with an inclined surface 11 that engages the expanding member 12, which is substantially inverted cone-shaped, in such a way that as the expanding member 12 moves, the supporting members will be moved laterally by their contact with the expanding member 12.

70 Openings are formed in the ribs 10 and 75 accommodate the coiled spring member 13 which is designed to normally hold the supporting members inwardly so that the inclined edges of the ribs 10 will engage the expanding member at all times.

75 This expanding member is formed with a central opening so that it may be positioned on the central supporting section in a manner to move longitudinally thereover, the expanding member being provided with a 80 threaded opening to accommodate the adjusting screw 14 that has its upper end positioned in the retaining member 15, the retaining member 15 being supplied with a suitable mark to cooperate with the markings 85 shown on the head 16 of the adjusting screw 14 so that movement of the adjusting screw to accomplish the adjustment of the standing member, may be made with a degree of accuracy.

90 The supports 8 are formed with cut out portions disposed throughout their lengths, to accommodate the boring elements 17 which may be secured in the cut out portion by means such as solder or the like. While 100 I have shown and described means such as solder, it is to be understood that any suitable securing means may be employed for securing the boring members within the supporting members.

105 A universal joint indicated at 18 connects the rod 19 with the central supporting section 5 and affords means whereby suitable power may be applied to rotate the supports within the cylinder.

110 In the use of the device, the device is positioned in a cylinder to be rebored and the

adjusting screw 14 operated to move the boring members into engagement with the wall of the cylinders, whereupon power is applied to rotate the central supporting section 5 which in turn imparts rotary movement to the supports mounted thereon.

From the foregoing it will be obvious that due to the construction shown and described, the supports together with their boring elements may be adjusted laterally adapting the device for use in connection with cylinders of various diameters.

I claim:-

1. A reboring device including a central supporting section, supporting rods extending laterally from the central supporting section, boring element supports having enlarged end portions, said end portions having openings to accommodate the supporting rods, ribs carried by the supports, said ribs having beveled inner surfaces, an expanding cone mounted for movement longitudinally of the central supporting member and adapted to engage the beveled inner surfaces of the ribs to move the supports laterally, means for moving the cone, and

means for normally holding the sections into close engagement with the cone.

2. A reboring device including a central supporting section, supporting rods extending laterally from the supporting section, boring element supports, said supports having enlarged end portions having openings to accommodate the supporting rods, ribs having beveled surfaces, secured to the supports, said ribs having openings disposed substantially centrally thereof and extending transversely therethrough, a coiled spring extending through the openings of the ribs for connecting the ribs, an adjusting cone movable along the support and adapted to engage the ribs for moving the supports laterally, means for moving the adjusting cone, and boring members carried by the supports.

In testimony that I claim the foregoing as my own, I have hereto affixed my signature in the presence of two witnesses.

JOHN P. DRESP.
